ATTORNEY

UNITED STATES PATENT OFFICE.

RUDOLPH LIEBMAN, OF NEW YORK, N. Y.

DESIGN FOR A PICTURE-FRAME.

SPECIFICATION forming part of Design No. 23,853, dated December 4, 1894.

Application filed November 1, 1894. Serial No. 527,676. Term of patent 3½ years.

To all whom it may concern:

Be it known that I, RUDOLPH LIEBMAN, a citizen of the United States of America, residing at New York, in the county and State of New York, have invented and produced a new and original Design for Picture-Frames, of which the following is a specification, reference being had to the accompanying drawing, showing a face view thereof.

10 The design illustrated in the accompanying drawing consists essentially in a substantially rectangular sight opening bounded by conventionalized flowers and leaves *a b*; which latter are surrounded by a rectangular

border *c* formed with alternate heart-shaped 15 bodies and scrolls. Outside of this border are represented leaves and blossoms terminating below in supports for the frame.

What I claim as new is—

The design for picture and analogous 20 frames, substantially as herein shown and described.

In testimony whereof I affix my signature in the presence of two witnesses.

RUDOLPH LIEBMAN.

Witnesses:

CHAS. W. THOMAS,
A. FABER DU FAUR.
